KEY FOR A DOOR LOCK

Paul H. Grevengoed, 1047 Alton SE.,
Grand Rapids, Mich.

Filed Mar. 25, 1960, Ser. No. 59,870

Term of patent 14 years

(Cl. D50—4)

FIG. 1

FIG. 2

Figure 1 is a plan view of the key for a door lock, showing my new design.

Figure 2 is a section taken on the line 2—2 of Figure 1.

The opposite side of the key shown in Fig. 1 is smooth and plain in appearance except for the shank, which is a mirror image of the shank as seen in Fig. 1.

I claim:

The ornamental design for a key for a door lock, as shown and described.
